H. COLOMB,
MEANS FOR SECURING BRIDGES OF TIMEKEEPING MECHANISM,
APPLICATION FILED SEPT. 28, 1921.

1,434,327.

Patented Oct. 31, 1922.

INVENTOR:

Henry Colomb
by Wm Wallace White
ATTY.

UNITED STATES PATENT OFFICE.

HENRY COLOMB, OF TAVANNES, SWITZERLAND.

MEANS FOR SECURING BRIDGES OF TIMEKEEPING MECHANISM.

Application filed September 28, 1921. Serial No. 503,996.

To all whom it may concern:

Be it known that I, HENRY COLOMB, a citizen of the Swiss Republic, residing at Tavannes, Canton of Berne, Switzerland, 5 have invented new and useful Improvements in Means for Securing Bridges of Timekeeping Mechanism, of which the following is a specification.

This invention relates to the construction 10 of time keeping mechanism, particularly watches, and has for its object an improved mounting for the bridges for the escapement mechanism and the like.

In the usual construction, the shaft carrying 15 the escape pinion and the escape wheel extends through the plate, with the pinion on one side thereof in engagement with the last wheel of the gear train of the time keeping mechanism, and the escape wheel on the 20 other side of the plate working with the anchor. This necessitates two bridges, one on each side of the plate, and since these bridges are customarily held in place by screws tapped into the plate, the plate is 25 weakened, and the six holes usually required render precision difficult to attain.

One object of my invention is to provide 30 a mounting for the bridges which will reduce the number of holes that are required through the plate. Further objects are to 35 provide means for accurately positioning and securing the bridges in place.

The invention consists in the construction, 40 arrangement and combination of parts herein described and claimed, and a preferred embodiment of which is illustrated in the accompanying drawings, in which—

The figure shows a section taken approximately on the center line of the escapement 45 frame.

Referring to these drawings, 1 designates the usual plate, upon which are mounted the bridges 2, 3, for the support of the escape pinion 4, escape wheel 6, and shaft 5 upon 50 which these are mounted, the shaft 5 passing through the opening 7 in the plate. The anchor 8 may be carried by a suitable shaft 9 mounted between the plate 1 and the bridge 2, and disposed for cooperation with the escape wheel 6.

The mounting of the bridges 2, 3 is effected by means of two or more pillars 10, having at each end a reduced portion or tenon, the tenon 11 being adapted to fit 55 snugly a hole 12 in the plate 1, and extend

through said plate to enter and fit snugly a hole 13 in the bridge 2, the tenon 11 projecting only part way into the bridge 2, and the bridge being held securely upon the plate and tenon by means such as the tap bolt 14 60 which likewise serves to hold the pillar fixed in the plate. The tenon 15 at the other end of the pillar 10 is adapted to fit snugly the hole 16 of the bridge 3, extending only part way through, so that the tap bolt 17 holds the 65 bridge 3 snugly upon the pillar 10, the distance of the bridge 3 from the plate 1 being determined by the distance between the shoulders forming the tenons 11, 15.

In connection with the foregoing it is to 70 be observed that the plate 1 and bridge 2 are provided with spacing bosses on their adjacent faces about the openings 12 and 13 to space said parts and thereby provide means for the mounting of the wheel 6. 75

Having now described my invention, I claim and desire to secure by Letters Patent:

1. In time keeping mechanisms, in combination, a plate having openings therethrough, bridges for the escapement mechanism and the like on opposite sides of the plate, one of the bridges being spaced from the plate, and means for securing the bridges to the plate comprising pillars having tenons formed at each end for cooperation with 85 certain openings in the plate and bridges, and means for clamping the bridges to said tenons.

2. In time keeping mechanisms in combination, a plate having openings therethrough, bridges for the escapement mechanism and the like on opposite sides of the plate, one of the bridges being spaced from the plate, and means for securing the bridges to the plate, comprising pillars having a 90 tenon at each end, the tenon at one end being adapted to support a bridge, means for holding the bridge thereon, the tenon at the other end being engaged through one of the openings in the plate for the support of the pillar, said latter tenon extending through said plate to engage the second bridge, and means for holding said second bridge on said pillar and thereby securing said pillar to the plate. 100

3. In time keeping mechanisms in combination, a plate having openings therethrough, bridges for the escapement mechanism and the like arranged on opposite sides of the plate, one of the bridges being spaced from the plate means for securing the 110

bridges to the plate, comprising pillars having a tenon at each end, the tenon at one end being adapted to support a bridge, a bolt tapped into said tenon for holding the bridge thereon, the tenon at the other end being engaged through one of the openings in the plate for the support of the pillar, said latter tenon extending through said plate to en-

gage the second bridge, and a bolt tapped into said tenon for holding said second bridge on said pillar and thereby securing said pillar to the plate.

In testimony whereof I have signed my name to this specification.

HENRY COLOMB.
